UNITED STATES PATENT OFFICE.

NELSON CURTIS, OF BOSTON, MASSACHUSETTS.

AUTOMATIC BOILER-FEEDING DEVICE.

SPECIFICATION forming part of Letters Patent No. 696,226, dated March 25, 1902.

Application filed July 2, 1900. Serial No. 22,376. (No model.)

To all whom it may concern:

Be it known that I, NELSON CURTIS, of Boston, in the county of Suffolk and State of Massachusetts, have invented certain new and useful Improvements in Automatic Boiler-Feeding Devices, of which the following is a specification.

This invention relates to improvements in automatic boiler-feeding devices whereby a constant level of the water in the boiler is automatically maintained.

The invention consists in the employment of a movable septum, preferably a flexible diaphragm, and a valve in a water-supply or controlling a water-supply controlled by the movements of said septum, the movements of the septum being controlled by the variations or differences in the pressures of two columns of water acting upon opposite sides of said septum. One of said columns of water is preferably substantially of an unvarying pressure and acts upon said septum to hold it so that it will so control the water-supply as to cause water to be fed through the supply-pipe and to the boiler in a quantity in excess of that converted into steam and carried off through the safety-valve or the discharge-pipe from the boiler and used by the engine or other places where steam is supplied from the boiler. The other column of water, which acts upon the septum, varies in amount from nothing to one equal to the first column, and this second column will cause the temporary shutting off of the supply of water to the boiler after said second column reaches a certain height and creates sufficient pressure on the septum in opposition to the first column to close the valve in the water-supply pipe, substantially as will be hereinafter fully described and claimed.

The invention is carried out substantially as illustrated on the accompanying drawings, forming an essential part of the specification, and whereon—

Figure 1 represents a plan view of the preferred arrangement of my improved device, showing a portion of the shell of a steam-boiler in section. Fig. 2 represents a vertical section on the line A B in Fig. 1. Figs. 3 and 4 represent different arrangements of parts of the device from that shown in Figs. 1 and 2.

Like characters of reference refer to like parts wherever they occur on the different parts of the drawings.

Referring to the arrangement of my device as shown in Figs. 1 and 2, to the shell of the boiler 1, of any desired construction, are attached the pipes 2 and 3. The pipe 2 is in open communication with the interior of the boiler somewhat above the level of the water desired to be maintained therein, and the pipe 3 is in open communication with the interior of the boiler somewhat below the level of the water desired to be maintained therein. The pipes 2 and 3 form means whereby my improved device is connected to the boiler and through which steam and water are conveyed to said device in order to cause its proper operation. My improved device, as illustrated in said Figs. 1 and 2, consists of a vertically-arranged pipe 4, connected at its upper end to the pipe 2 and near its lower end to the pipe 3. The pipe 4, of any desired length, is in open communication at its lower end with a chamber 5, located within the upper portion of a casing 6, made in two parts, the lower portion of said casing forming a second chamber 7, which is separated from the chamber 5 by means of a movable septum, shown on the drawings as consisting of a flexible diaphragm 8, firmly clamped at its edge between the two parts of the casing. Firmly secured to the upper side of the diaphragm 8 is a tube 9, which extends upward within the pipe 4 and has its upper open end substantially on a level with the desired level of the water to be maintained in the boiler. The lower end of the tube 9 is in open communication with the chamber 7 by means of the passage 10 or in any other equivalent manner.

From the above description it will be seen that water from the boiler will be admitted to the pipe 4 through the pipe 3 and will rise in the pipe 4 to a level with the top of the water in the boiler; also, that steam from the boiler will be admitted to the pipe 4 through the pipe 2 and will press upon the upper surface of the diaphragm through the column of water contained within the pipe 4 and the water within the chamber 5 with a pressure substantially equal to the boiler-pressure. Steam from the boiler will also press against the under surface of the diaphragm with the

same pressure either through a column of water contained in the tube 9, as hereinafter described, or directly by being conveyed through the tube 9 and passage 10 to the chamber 7. As the steam-pressure upon the water in the pipe 4 upon the upper surface of the diaphragm is equal to the steam-pressure on the under side of the diaphragm, it will be seen that said steam-pressures neutralize each other and do not effect the diaphragm to move it in either direction; but as the upper surface of the diaphragm is at all times subjected to the additional and substantially uniform pressure due to the pressure of the water in the chamber 5 and pipe 4, which it sustains, said diaphragm is deflected from its normal position by this additional pressure of the water. If the water in the pipe 4, which is normally level with the top of the tube 9 therein, should rise from any cause so as to overflow and enter the tube 9, it would be conveyed through said tube and passage 10 to the chamber 7 and after filling said chamber would gradually rise in the tube 9, causing an additional pressure on the under side of the diaphragm over that of the steam-pressure thereon due to the weight of this column of water, which additional pressure would gradually increase as the tube 9 is filled, and when said tube becomes full would equal the additional water-pressure on the upper side of the diaphragm, and the water-pressure on both sides of the diaphragm would then neutralize each other, leaving the diaphragm at its normal shape uninfluenced by uneven pressures.

Within a pipe 11, which may lead either from a supply of water to the feed-pump of the boiler or from a supply of motive fluid to operate said feed-pump, is a valve 12, which is connected to the under side of the diaphragm 8 by the valve-stem 13, and said valve is controlled by the movements of said diaphragm. A small passage 14 connects the chamber 7 with the water-supply pipe between the valve controlling said pipe and the feed-pump, or said passage may connect said chamber with a suitable waste. The passage 14 forms a contracted waste-passage for the chamber 7 and the tube 9, through which the water from said parts may slowly discharge after it has accomplished the object for which it was admitted to said parts. The valve 12 is so arranged that a downward movement of the diaphragm will cause the opening of the valve and cause the operation of the feed-pump or the supply of water through the supply-pipe to the feed-pump, and said valve is arranged so that it will remain slightly open while the feeding device is in operation, with the diaphragm slightly depressed from its normal shape, due to the water pressing on the upper side thereof being in excess of the water pressing on its under surface, but said valve 65 will be closed if the diaphragm assumes its normal shape, free from unequal pressures thereon. It will be understood that the weight

of the column of water within the pipe 4 and sustained by the upper surface of the diaphragm when not opposed by a water-pressure on the under surface of the diaphragm is such as to depress the diaphragm sufficiently to operate the valve 12 and cause a supply of water to the boiler in excess of that which can possibly be used by the boiler, and that the quantity of water thus fed is automatically adjusted by my device to equal that used by the boiler, as the water will overflow into the tube 9 and gradually filling said tube will create a counteracting pressure on the under surface of the diaphragm tending to close the valve and reduce the supply to the boiler. Therefore the water in the boiler will be maintained at the desired level. If there is no steam being discharged from the boiler, and therefore no water being used to make steam, the column of water in the pipe 4 will remain at a level with the water in the boiler, but the column of water within the tube 9 will gradually pass away through the passage 14, and removing the pressure from the under side of the diaphragm caused by this column of water will allow the pressure on the upper side of the diaphragm to open the valve 12 to its fullest extent.

From the above description of my device it will be seen that the operating power used to control the supply of water to the boiler is the differences in the weights or pressures of the two columns of water acting on the opposite sides of the movable septum or diaphragm, one of which columns is of substantially a constant weight or pressure, while the other is variable from nothing to that equal to the first column, and it will be understood that the range of variations, and consequently the amount of available power for this purpose, will be increased by increasing the weight or pressure of the constant column of water which is contained within the pipe 4 and acts on the upper surface of the diaphragm. This increase may be obtained by extending the pipe 4 downward the desired distance below the level of the water in the boiler. It will also be seen that the position of the top of the tube 9 determines the level of the water in the boiler irrespective of the position of the movable septum.

In Figs. 1 and 2 I have illustrated what I consider the preferred arrangement of my device, as the same can then be sold intact and ready to be attached to any boiler, but my device is capable of being arranged in other ways and accomplish the desired result. I have shown two arrangements of the device in Figs. 3 and 4.

In Fig. 3 I have shown the casing 6 as being outside the shell of the boiler, the pipes 2 and 4 as being dispensed with, and the pipe 3 as connected with the upper half of the casing and forming an open communication between the interior of the boiler and the chamber 5, the water in the boiler constituting in part the column of water which presses

against the upper surface of the diaphragm. The tube 9 is disconnected from the diaphragm, connected to the lower part of the casing 6, carried into the boiler, and extended 5 within the boiler, so that its upper open end is at the desired level to be maintained within the boiler. The operation of this arrangement of the device is the same as that described in relation to Figs. 1 and 2 and needs no further description.

In Fig. 4 I have shown the device arranged substantially as in Figs. 1 and 2, excepting that the tube 9 is removed from the interior of the pipe 4, is disconnected from the diaphragm, but is connected at its lower end to the lower portion of the casing 6, with which it is in open communication, and has its upper end connected to the pipe 4 at a level with the desired level of the water to be maintained in the boiler.

It will be understood that the operation of the device as illustrated in Fig. 4 is the same as that described in relation to the other figures of the drawings and needs no further description.

Although I have shown different arrangements of my device on the drawings, I wish it to be understood that there are still other arrangements of the device within the scope 30 of mechanical skill which might be employed without departing from the spirit of my invention, and that I do not confine myself to the precise arrangements shown.

Thus far I have described my device as being used to maintain a desired level of the water in a boiler; but it is equally applicable to any other receptacle in which a desired level is to be maintained.

This my improved boiler-feed is very simple in construction, effective in operation, is not liable to get out of order, there being no finely-adjusted parts to become disarranged. The device is operated without the use of floats and does not depend upon the expansion or contraction of its parts for its proper operation. It is especially applicable to boilers used in automobiles or in other places where steam is supplied to operate engines or other devices which are to be controlled 45 or operated by persons with rather limited experience and knowledge of the requirements in running machines of such description.

Having thus fully described the nature, construction, and operation of my invention, I wish to secure by Letters Patent and claim—

1. In an automatic feeding device for boilers or other receptacles in which it is desired to maintain a given level of the water contained therein, a movable septum, two columns of water acting in opposition to each other to move said septum by variations in the relative weights of said columns, the water in one of said columns being substantially 65 constant at a level with and controlled by the water in the boiler or other receptacle, and

the water in the other column being variable according to the amount of water being used by the boiler or other receptacle, a contracted waste-passage for the latter column of water, 70 a water-supply, and a valve controlling said supply and controlled by the movements of said septum, for the purpose set forth.

2. In an automatic feeding device for boilers or other receptacles in which it is desired 75 to maintain a given level of the water contained therein, a casing having its interior in open communication with the interior of the boiler or other receptacle above and below the desired level of the water to be maintained 80 therein, a movable septum dividing said casing into two chambers, means to establish free admission of the water in the boiler to one of said chambers to create a column of water in said chamber at a level with the water in the 85 boiler or other receptacle and to act on one side of said septum, means to prevent the admission of water from the boiler or other receptacle to the other of said chambers, to act on said septum in opposition to the column of 90 water in the first-named chamber, except when the water in the boiler or other receptacle exceeds the desired level of water to be maintained therein, a contracted waste-passage 95 for the latter chamber, a water-supply, and a valve controlling said supply controlled by the movements of said septum, for the purpose set forth.

3. In an automatic feeding device for boilers or other receptacles in which it is desired 100 to maintain a given level of the water contained therein, a casing, a movable septum dividing said casing into an upper and lower chamber, a pipe in open communication with said upper chamber, means to connect said pipe with the boiler or other receptacle above and below the desired level of the water to be maintained therein and form free communication between said parts, a tube carried by said septum in open communication with the 105 lower chamber in said casing extending upward from said septum to the desired level of the water to be maintained within the boiler or other receptacle, a contracted waste-passage 110 for the lower chamber, a water-supply, and a valve connected to said septum controlling said supply, for the purpose set forth.

4. In an automatic feeding device for boilers or other receptacles where it is desired to maintain a given level of the water contained 115 therein, a casing having its interior in open communication with the interior of the boiler or other receptacle above and below the desired level of the water to be maintained therein, a movable septum dividing said casing into two chambers, means to establish free admission of the water in the boiler to one of said chambers to create a column of water in said chamber at a level with the water in the boiler or other receptacle and to act 120 on one side of said septum, means to prevent the admission of water from the boiler or other 125 receptacle to the other of said chambers, a contracted waste-passage for the latter chamber, a water-supply, and a valve connected to said septum controlling said supply, for the purpose set forth.

receptacle to the other of said chambers, to act on said septum in opposition to the column of water in the first-named chamber, except when the water in the boiler or other receptacle exceeds the desired level of water to be maintained therein, a contracted waste-passage from the second-named chamber to gradually discharge the water therefrom, a water-supply, and a valve controlling said

supply controlled by the movements of said septum, for the purpose set forth.

In testimony whereof I have affixed my signature in presence of two witnesses.

NELSON CURTIS.
